UNITED STATES PATENT OFFICE.

GUSTAVE H. JANTZ, OF WYOMING, OHIO.

WRINGER ROLLS FOR CLOTHES WRINGERS.

Application filed September 3, 1920. Serial No. 407,839.

To all whom it may concern:

Be it known that I, GUSTAVE H. JANTZ, a citizen of the United States, residing at Wyoming, in the county of Hamilton and State of Ohio, have invented certain new and useful Improvements in Wringer Rolls for Clothes Wringers, of which the following is a specification.

It has been a usual practice heretofore in making clothes wringers to provide the shafts of the wringer rolls with meshing cog-gears so as to drive one wringer roll shaft from the other wringer roll shaft. This has been done to provide a positive driving connection between the wringer rolls. It has been found in practice that, if the wringer rolls, as heretofore constructed, receive a coating of soapy slime, as happens in the use of the wringer, the driving wringer roll will, in the absence of such meshing gearing between the wringer roll shafts, fail to afford sufficient traction for the opposed wringer roll, to rotate the latter, with the result that, if it is attempted to put clothes between the wringer rolls, the wringer rolls will not grip the clothes to draw the clothes between the wringer rolls, but the driving wringer roll will merely turn without having tractive force either upon the opposed wringer roll or the clothes.

It is the object of my invention to so construct the wringer rolls, as to insure tractive force between them in the absence of meshing gearing between the wringer roll shafts.

It is the further object of my invention to provide wringer rolls with coacting tractive sections arranged to drive one wringer roll from the other wringer roll, and, further, to provide the wringer rolls with portions whose primary function is to maintain driving relation between coacting wringer rolls.

The invention will be further readily understood from the following description and claims, and from the drawings, in which latter:

Fig. 1 is a side elevation of a wringer embodying wringer rolls, to which my invention is applied.

Fig. 2 is an enlarged side elevation show-

ing one end of the wringer rolls and frame.

Fig. 3 is an end elevation of the wringer rolls, the shafts being shown in cross-section on the line 3—3 of Fig. 2. 55

Fig. 4 is an axial section of the same taken on the line 4—4 of Fig. 3.

Fig. 5 is an end elevation of a pair of coacting wringer rolls having a slightly different arrangement of coacting tractive sections, the shafts being shown in cross-section. 60

Fig. 6 is an axial section of the same, partly broken away, taken on the line 6—6 of Fig. 5. 65

Fig. 7 is a side elevation of a pair of coacting wringer rolls, partly broken away, showing a modification of my improved device.

Fig. 8 is an end elevation of the same, the roll shafts being shown in cross-section. 70

Fig. 9 is an axial section of the same, taken on the line 9—9 of Fig. 8.

Fig. 10 is an end elevation of a pair of coacting wringer rolls, showing a further modification of my improved device, the shafts being shown in cross-section. 75

Fig. 11 is an axial section of the same, partly broken away, taken on the line 11—11 of Fig. 10, and, 80

Fig. 12 is an end elevation of a pair of coacting wringer rolls, showing a still further modification of my invention, the shafts being shown in cross-section.

21 represents a usual frame of a clothes wringer, which may be of suitable construction. Wringer rolls are usually arranged in pairs in the clothes wringer. Suitable means are provided for imparting rotation to one of the wringer rolls. These means 85 may be manual means or power driven means, as may be desired.

I have shown power driven means comprising a bevel-gear 22, which is driven for instance by a shaft 23, journaled in a bearing 24, and meshing with bevel-gears 25, 26, normally loose about the shaft of one of the wringer rolls. 95

A clutch-collar 28 has spline connection 29 with said shaft, the said clutch-collar and the respective bevel-gears 25, 26, being provided with the coacting teeth of clutches 31, 100

32. A shifting lever 33 is provided for engaging the clutch-collar with either of the bevel gears 25, 26, for driving the wringer roll shaft in either direction.
33. Wringer rolls 41, 42, are shown, constituting a pair of wringer rolls. The shaft 43 of the wringer roll 41 is arranged to rotate in bearings 44 in the frame, and the shaft 45 of the wringer roll 42 is arranged to rotate 10 in bearings 46. The bearings 46 slide in guideways 47 in the frame. Pressure means are provided for exerting pressure between the wringer rolls when wringing clothes. A spring 48 may be employed to exert this 15 pressure, being shown adjustable by means of a screw 49, threaded in a bearing 50 on a cross-bar 51 of the frame. The mounting, driving and pressure means may be of any usual or desired form or construction.
20. I have dispensed with the usual cog-gears between the wringer rolls. In order to insure driving relation between the coacting wringer rolls, I provide the wringer rolls with tractive portions which engage each 25 other to coact for insuring frictional driving relation between the wringer rolls. These tractive portions may assume different forms, and I have exemplified five such forms in the drawings. It is obvious that 30 the various forms may be employed coactively, or one form may coact with another, or one or both ends of the wringer rolls may be provided with my invention, or other changes be made, without departing 35 from the spirit of my invention within the scope of the appended claims.
- Referring to Figs. 1, 2, 3 and 4, I have provided the wringer roll with a tractive section 55, exemplified as arranged about 40 the axis of the wringer roll, and formed in the material of the body, for instance, rubber, of the wringer roll. One of these tractive sections is shown located at each 45 end of the wringer-roll. This tractive section or roughened section of the wringer roll is exemplified as recurrent protuberances or ridges and grooves, arranged about the axis of the wringer roll, at the end or ends of the wringer roll. They form tractive 50 transmission sections of the rolls to transmit rotation from one of the rolls to the other of the rolls.
- Referring to Fig. 1, the tractive sections, whatever their form, may have shields 57 55 received thereover, the shields being suitably secured to the frame of the machine. End collars 58 are provided on the wringer-roll. Each of the end collars is shown located on a reduced annular step 60 of the shaft, 60 against an annular shoulder 61 formed by the reduction of said shaft, the outer end of said annular step being upset, as shown at 62, against the outer face of the collar to hold it in place. The tractive section pref- 65 erably surrounds the collar.

In the form shown in Figs. 1, 2, 3 and 4, the diameters of the tractive sections are preferably substantially the same as the diameters of the expressing portions 59 of the rolls. The pressure brought to bear on the shafts of the rolls by the spring means of the wringer frame cause pressure between the coacting rolls, pressure being also consequently exerted between the tractive sections of said rolls, so that, even if there should be soapy slime on the wringer rolls, the roughened or ribbed tractive sections will cause rotative tractive transmission from one of the wringer rolls to the other of the wringer rolls, with sufficient force to cause a piece of fabric or clothes to be gripped between the wringer rolls and to draw the same in between the rolls.

When the clothes have been once gripped between the wringer rolls, the clothes act as a medium to cause transmission of rotation from the driving wringer roll through the clothes to the opposed wringer roll for maintaining rotation of the opposed wringer roll when once the clothes have been started between the rolls.

The presence of the clothes causes a relief or separation between the tractive sections and relieves these tractive sections from wear, the tractive sections being preferably protected from contact by the goods by the shields 57. The principal wear upon the wringer rolls takes place in those portions thereof which are contacted by the clothes, and serve to express the water from the clothes, and, as most of the rotation of the wringer roll takes place while clothes are located between the rolls, the driving faces of the tractive sections of the wringer rolls are preserved, and maintenance of contact between coacting tractive sections is assured, due to the greater wear of the expressing portions of the rolls.

I have in Figs. 5 and 6 shown a similar form of tractive section 65 for the rolls, comprising ribs and spaces between the ribs, similar to the ribs and spaces of the tractive transmission section 55, the circle in which the crowns or outer peripheries of the ribs is located, being of greater diameter than the cylinder of the roll. In this construction greater pressure is brought to bear between the tractive sections of the rolls when the wringer rolls are in coacting pressure relation, for affording additional tractive force.

In the forms shown in Figs. 1 to 6 inclusive, the tractive sections are shown as integral with the body 53 of the roll, being formed for instance by forming the mold in which the wringer roll is molded with counterparts of the ribs and spaces between the ribs, so as to form the ribs and the spaces between the ribs, on the rolls at the same time that the body of the roll is formed, and of the same material as the material, for in-

stance, rubber, of the body of the roll, the whole being vulcanized together to form an integral structure.

In the form shown in Figs. 1 to 6 inclusive there is pressure brought to bear between the tractive sections of the coacting rolls to cause tractive transmission of rotation from the driving wringer roll to the driven wringer roll. This pressure is greater in the form shown in Figs. 5 and 6. The pressure tends to resiliently flatten or distort the tractive sections one upon the other for enhancing the tractive transmission, as clearly shown in Figs. 3 and 4, and in Figs. 5 and 6.

I have, in Figs. 7, 8 and 9, shown a further modification, in which the friction or tractive transmission section of the roll comprises a band 75, this band being shown of 20 slightly greater diameter than the body 73 of the roll. These bands are preferably of a softer or more yielding rubber than the rubber of the body of the roll, but are preferably vulcanized with the body of the roll, 25 so as to firmly adhere thereto or become amalgamated therewith and form an integral structure, one or both ends of the rolls may be provided with these bands.

When pressure is applied between the 30 rolls in this exemplification of my invention, the friction bands are compressed upon the respective bodies of the rolls for resiliently flattening or distorting the contact portions of said bands and compelling tractive transmission of rotation from the driving wringer roll to the driven wringer roll by means 35 of said bands. The distortion of the band is communicated somewhat to the body of the roll, all as clearly shown in Figs. 7, 8 and 9. In this form also there is separation 40 between the wringer rolls when the goods have been received between the wringer rolls, thereby relieving pressure between said friction or tractive transmission sections.

I have, in Figs. 10 and 11, shown a further modification in which friction bands 85 are employed which are received in rabbets 86 in the ends of the bodies 83 of the wringer rolls. These bands are preferably of 50 softer or more yielding rubber than the bodies of the rolls, and are preferably vulcanized in said rabbets, so as to become amalgamated with said bodies, and form an integral structure with the bodies. They 55 preferably extend radially beyond the periphery of the bodies of the rolls for having firmer contact when pressure is brought to bear upon the rolls. One or both ends of the rolls may be provided with said 60 bands.

The compressive action upon said bands extends into the cylindrical projection of the rolls and the distortion extends over a greater area and to a greater depth radially than 65 in the form shown in Figs. 7, 8 and 9, there-

by lending additional traction between the rolls, which distortion or action of the tractive transmission portion is clearly indicated in Figs. 10 and 11.

I have in Fig. 12 shown a form similar 70 to that shown in Figs. 10 and 11, with this addition, that the bands 95 are provided with peripheral protuberances 94, shown as ribs and spaces between the ribs, the band being otherwise similar to the band 85, and received in an annular rabbet 96 in the body of the wringer-roll, the expressing section of which is indicated at 99. The band is preferably vulcanized to the body to form an integral structure. The resilient protuberances aid in the tractive transmission of 80 rotation between the wringer rolls.

Having thus fully described my invention, what I claim as new, and desire to secure by Letters Patent, is:

1. A wringer roll comprising an expressing section, and a tractive section provided with resiliently yielding protuberances.

2. A wringer roll comprising an expressing section, and a tractive section of greater 90 diameter and resiliently yielding properties than the diameter and resiliently yielding properties of said expressing section.

3. A wringer roll comprising an expressing section and a tractive resilient section 95 more yielding than said expressing section, said sections being of rubber compositions.

4. A wringer roll comprising an expressing section and a tractive resilient section at each end of said expressing section, said 100 tractive resilient sections being more yielding than said expressing section.

5. A wringer roll comprising an expressing section and a tractive resilient section, said tractive resilient section provided with 105 resilient ribs and spaces between said ribs, said ribs and spaces arranged about said tractive resilient section.

6. A wringer roll comprising an expressing section and a ribbed tractive section 110 more yielding than said expressing section.

7. In a clothes wringer, the combination 115 of coacting wringer rolls comprising opposed expressing sections, and opposed tractive sections provided with resiliently yielding protuberances arranged to opposingly crush each other for driving connection between said rolls.

8. A wringer roll comprising a resiliently yielding expressing section, a collar at the 120 end of said resiliently yielding expressing section, and a tractive section more resiliently yielding than said expressing section surrounding said collar.

9. In a clothes wringer, the combination 125 of a pair of elastic wringer rolls comprising a peripheral portion having greater elastically yielding properties than the balance of the peripheral portion of the wringer roll on which said peripheral portion of greater 130

elastically yielding properties is located, said portion having such greater elastically yielding properties normally having tractive connection with the opposing roll and arranged to be compressed thereby, and thereby to form a driving connection between said wringer rolls.

In testimony whereof, I have hereunto signed my name in the presence of two subscribing witnesses.

GUSTAVE H. JANTZ.
In presence of—
DELMA WERNING,
JAMES J. FITZPATRICK.
